Attorney

UNITED STATES PATENT OFFICE

JOSEPH W. HAWKS, OF SCRANTON, PENNSYLVANIA, ASSIGNOR TO THE WILLIAMS BAKERY, OF SCRANTON, PENNSYLVANIA, A CORPORATION OF PENNSYLVANIA

FOOD PACKAGE

Application filed March 25, 1932. Serial No. 601,234.

My invention relates to a food product, particularly with reference to a means of packaging and preserving the palatability of baked pies or similar food products by providing means whereby such articles formed and baked in pans of such side formation as to be generally unfitted for wrapping in machines adapted to right-angularly shaped objects may be wrapped in such machines, and at the same time making such package of such shape and character as to promote crispness and preserve freshness in the product rather than allowing it to become soggy and stale.

15 Referring to the drawings:

Figure 1 is an end view of the container comprising my invention, illustrating its shape when completely collapsed.

20 Figure 2 is an end view of the same container, illustrating the various folds, or hinges, in the blank as the container is shaped for use.

25 Figure 3 is a top plan view of the container as shown in Figure 2 with angles formed by the top median hinge 1 leveled.

Figure 4 is an end view of the container, illustrating its shape after angles formed by the bottom median hinge 2 have been leveled.

30 Figure 5 is an end view of the container illustrating the manner in which the inner tray section is formed and suspended from the outer section.

35 Figure 6 is a perspective view showing the finished package with the pie in place in the inner tray section, and with transparent wrapping applied.

40 Figure 7 is a cross-sectional view of the finished package on line 7-7 of Figure 6.

Figure 8 is an elevational view of a blank for another style of container comprising the features of my invention.

45 Figure 9 is an end view of the blank illustrated in Figure 8 partly folded on its various hinges to form the tray container.

Figure 10 is an end view of the container when fully formed.

50 Figure 11 is a perspective view of the completed package including the pie or other article of food placed therein, and wrapped.

The drawings (Figures 1, 2, 3, 4, and 5) illustrate the various folds in the blank forming the container, or tray for the pie. Figure 1, particularly, shows the manner in which the container is flattened by folding 55 on the longitudinal median hinges 1 and 2 in the inner tray section 3 and outer tray section 4 respectively.

As shown in Figure 3, flaps 5, 6 integral with the bottom of the inner tray section 3 may be formed by perforating or stamping what would otherwise be the sides thereof, or such flaps could be secured to the outer sides of the inner tray section in the usual manner.

These flaps are of sufficient width to impinge against the inner sides of the outer section 4 when the container is fully opened, as shown in Figures 5 and 7, and by dotted lines in Figure 6. The dotted lines in Figures 5 and 7 indicate an alternative method of forcing said flaps downwardly into the corner and abutting the outer section. Both methods are effective in reinforcing the container against collapse sideways.

The flaps 5, 6 may, of course, be made long enough to fold parallel against the inner sides of the outer section 4 where they could be secured (as by pasting) if so desired.

When the pie 7 is placed in the inner tray section 3, being shaped to fit snug against the sides and bottom, it is effective in reinforcing the inner tray against side movement, so that the combined effect of the shape of the pie and the lateral flaps 5 and 6 is the formation of a relatively steady package for inserting into the wrapping machine.

It is advisable in the case of baked food products having a liquid or moist center to prevent against their becoming soggy through seepage of the center through the crust. Apertures such as that formed by the cutting out of the flaps 5, 6 from the sides of the inner tray section 3, aided by additional apertures in the sides of said tray if necessary, allow access of the air in the air space formed around the inner tray section in the manner shown in Figures 5, 6, 7 to the product's crust and are effective in

65

creating a crispness in the crust and otherwise preventing it from assuming the undesirable soggy characteristic.

Except for the air in such air chamber, 5 wrapping in wax paper 8 (as shown in Figure 6) keeps the product substantially air tight, free from contamination, and preserves the shape of the package, including the air space between the inner tray section and the outer tray section of the container.

Referring to Figures 8 to 11, illustrating another form of package comprising various features of my invention, the blank (Figure 15) 8) comprises flaps 1, 2 integral with the section forming the base of the tray, and flaps 3, 4, which are integral with the section forming the extremes of the blank.

When the blank is folded on its hinges 20 as shown in Figure 9 the flaps 1, 2 remain in horizontal position and by their removal from the plane of the surrounding portion of the blank from which they are formed create apertures in the blank comprising the inclined sides of the inner tray, as shown by the dotted lines in Figure 11. These apertures may be supplemented by others punched in the sides of such tray, if so desired, for the purposes hereinbefore explained.

30 The extremities of the blank are then folded as shown in Figure 10 and the flaps 3, 4 forced through the longitudinal apertures in the sides 5, 6 of the inner tray, the ends of such flaps forming a retaining means by 35 their contact with the inner sides of the tray section. It will be noted that the outer sides 7, 8 of the container are substantially vertical, and the flaps 3, 4 form a means of sustaining any article placed in the inner tray section slightly above the bottom thereof.

40 As additional means for cooperating with the flaps 3, 4 in sustaining the article of food in the tray above the bottom thereof so as to 45 allow air contact with the bottom of said article of food, the portion of the blank comprising the bottom of the inner tray between the lateral flaps 1, 2 (except that portion 50 covered by the inwardly extending flaps 3, 4) may be corrugated or molded in any of the usual ways to sustain the article of food above the normal level of the bottom by contact with it at various points throughout 55 its bottom area.

The space thus formed under the article placed in the container, combined with the spaces between the side members 5, 7 and 6, 8 forms air chambers under the article and 60 along the sides of the tray containing it, and allows access of the air in such chambers to the products crust.

When the pie or similar article is placed in the container just described, and the waxed 65 paper wrapper applied to the whole, the ap-

pearance of the package is substantially as shown in Figure 11.

It will be noted that, as shown in Figure 7 and Figure 11, the contour of the package, with the article of food therein and before 70 wrapping, presents a box-shaped appearance and may then be wrapped in the type of wrapping machine adapted to such types of packages, rather than necessitating a special 75 type of wrapping such as would be necessary to wrap the pie without the cardboard container.

Having thus described my invention, I claim:

1. In a food package, an integral open-ended cardboard tray comprising an outer right-angularly U-shaped section and an inner section formed by walls extending downwardly and inwardly from the edges of said outer section. 80

2. In a food package, an integral open-ended cardboard tray comprising an outer right-angularly U-shaped section and an inner section formed by walls extending downwardly and inwardly from the edges of said outer section and means for sustaining the 85 contents of said tray off the bottom thereof. 90

3. In a food package, an integral open-ended cardboard tray comprising an outer right-angularly U-shaped section and an inner U-shaped section suspended from the edges of said outer section, said inner section having apertures in the sides thereof. 95

4. In a food package, an integral open-ended cardboard tray comprising an outer right-angularly U-shaped section and an inner U-shaped section suspended from the edges of said outer section, and outer wall impinging flaps extending from said inner section. 100

5. In a food package, an integral open-ended cardboard tray comprising an outer right-angularly U-shaped section and an inner U-shaped section suspended from the edges of said outer section and having apertures in the sides thereof, and outer wall impinging flaps extending laterally from said inner section. 110

6. In a food package, an integral open-ended cardboard tray comprising an outer right-angularly U-shaped section and an inner U-shaped section suspended from the edges of said outer section and having apertures in the sides thereof, and outer wall impinging flaps extending laterally from said inner section and formed by the portions of the sides thereof normally closing said apertures substantially as described. 115

7. An integral collapsible cardboard tray comprising a blank with hinged folds forming an outer U-shaped section and an inner U-shaped section suspended from the edges of said outer section, and a longitudinal median hinge in each of said U-shaped sections. 125

8. An integral collapsible cardboard tray 130

comprising a blank with hinged folds forming an outer U-shaped section and an inner U-shaped section suspended from the edges of said outer section, a longitudinal median hinge in each of said U-shaped sections, and outer wall impinging flaps extending from said inner section.

9. An integral collapsible cardboard tray comprising a blank with hinged folds forming an outer U-shaped section and an inner U-shaped section suspended from the edges of said outer section, a longitudinal median hinge in each of said U-shaped sections, said inner section having apertures in the sides thereof, and outer wall impinging flaps extending from said inner section.

10. An integral collapsible cardboard tray comprising a blank with hinged folds forming an outer U-shaped section and an inner U-shaped section suspended from the edges of said outer section and having apertures in the sides thereof, a longitudinal median hinge in each of said U-shaped sections, and outer wall impinging flaps extending laterally from said inner section and formed by portions of the sides thereof normally closing said apertures.

11. An integral collapsible cardboard tray comprising a blank with hinged folds forming an outer U-shaped section and an inner U-shaped section suspended from the edges of said outer section and having apertures in the sides thereof extending from their bases, outer wall impinging flaps extending laterally from the base of said inner section and formed by the portions of the sides thereof normally closing said apertures, and a longitudinal median hinge in each of said U-shaped sections, substantially as shown and described.

12. An integral collapsible cardboard tray comprising a tubular blank with longitudinal hinged folds forming an outer U-shaped section and an inner U-shaped section suspended from the edges of said outer section, and a longitudinal hinge in each of said sections bisecting said tubular blank.

13. An integral collapsible cardboard tray comprising a tubular blank with hinged folds forming an outer U-shaped section and an inner U-shaped section suspended from the edges of said outer section, a longitudinal hinge in each of said sections bisecting said tubular blank, and outer wall impinging flaps extending from said inner section.

14. An integral collapsible cardboard tray comprising a tubular blank with hinged folds forming an outer U-shaped section and an inner U-shaped section suspended from the edges of said outer section, a longitudinal hinge in each of said sections bisecting said tubular blank, said inner section having apertures in the sides thereof, and outer wall impinging flaps extending from said inner section.

15. An integral collapsible cardboard tray comprising a tubular blank with hinged folds forming an outer U-shaped section and an inner U-shaped section suspended from the edges of said outer section and having apertures in the sides thereof, a longitudinal hinge in each of said sections bisecting said tubular blank, and outer wall impinging flap extending laterally from said inner section and formed by portions of the sides thereof normally closing said apertures.

16. An integral collapsible cardboard tray comprising a tubular blank with hinged folds forming an outer U-shaped section and an inner U-shaped section suspended from the edges of said outer section and having apertures in the sides thereof extending from their bases, outer wall impinging flaps extending laterally from the base of said inner section and formed by the portions of the sides thereof normally closing said apertures, and a longitudinal hinge in each of said sections bisecting said tubular blank, substantially as shown and described.
